CHARLES RAPHAEL KUZELL, OF CLARKDALE, ARIZONA, ASSIGNOR TO UNITED VERDE COPPER COMPANY, A CORPORATION OF DELAWARE

FURNACE CHARGING DEVICE

Application filed May 5, 1930. Serial No. 449,926.

This invention relates to metallurgy and has for an object the provision of improved metallurgical apparatus. More particularly, the invention contemplates the provision of an improved apparatus for introducing molten materials into metallurgical furnaces.

In various types of metallurgical operations it is customary to introduce molten materials into furnaces. In such cases, the molten materials are introduced through the side wall portions of the furnaces in which the temperatures are sufficiently high to maintain the materials in a molten condition. Thus, for example, in copper smelting operations, molten converted slags are frequently charged into the firing end portions of reverberatory furnaces for retreatment. In charging molten materials into furnaces through the side walls it is necessary that conduits or launders be provided and that the conduits or launders extend to points within the furnaces in order that the molten materials may be deposited on the hearths or on the charges on the hearths. The conduits or launders employed are therefore subjected to the intense heat within the furnaces as well as the heat and corrosive actions of the molten materials, and considerable difficulty has been experienced heretofore in providing conduits or launders of suitable constructions and materials to resist, satisfactorily, decomposition and destruction under the conditions to which they are subjected. Some difficulty has been experienced, also, in providing means for closing the charging opening satisfactorily at the completion of a charging operation.

The present invention contemplates the provision of a charging device for molten materials which is capable of being used advantageously under the conditions to which such devices are normally subjected. The invention further contemplates the provision of a charging device provided with improved means for closing the charging opening at the completion of a charging operation. The invention further contemplates the provision of a reverberatory furnace provided with improved means for introducing molten material thereinto.

A charging device formed in accordance

with the invention comprises a launder or conduit having cooling means associated therewith. The launder or conduit may be of any suitable length and cooling means may be associated with all or any part thereof. In the preferred form of the device, cooling means are provided for that portion adjacent the end which extends through the furnace wall. The device is preferably in the form of a launder, a portion of which is open at the top. A cover is preferably provided for the portion adjacent the end which extends through the furnace wall. The covered end portion is preferably provided with one or more passages through which a cooling fluid such, for example, as water may be circulated. A movable gate is associated with the covered end portion for closing the charging opening at the completion of charging operations.

In its application to reverberatory furnaces, one end portion of the device extends through an opening in a side wall of the furnace near the firing end. The end of the device may be substantially flush with the inner surface of the wall through which it extends or it may project a short distance beyond. The opening in the furnace wall is preferably of just sufficient size to receive the charging device in order that a substantially gas tight joint around the device may be provided. The gate or closure member is preferably disposed exteriorly of the furnace. Each reverberatory furnace is preferably provided with two charging devices, one disposed on each side of the firing end.

The invention will be better understood from a consideration of the following description in conjunction with the accompanying drawings in which

Fig. 1 is an elevation of a charging device embodying the invention, showing it applied to a reverberatory furnace, a portion of the furnace being shown in section;

Fig. 2 is a plan of the apparatus shown in Fig. 1;

Fig. 3 is an enlarged elevation of a portion of the apparatus shown in Fig. 1;

Fig. 4 is a section taken substantially along line 4-4 of Fig. 3;

Fig. 5 is a section taken substantially along line 5—5 of Fig. 4;

Fig. 6 is a section taken substantially along line 6—6 of Fig. 3; and

Fig. 7 is a section taken substantially along line 7—7 of Fig. 5.

The drawings show a reverberatory furnace 10 having two charging devices extending through openings in a vertical wall at the firing end thereof. The furnace is provided with the usual conduits 11 for introducing combustible mixtures of air and powdered coal. Suitable frames 12 are provided for supporting the charging devices. The charging devices extend through openings immediately adjacent the top wall or roof 13.

Each charging device is in the form of a launder comprising a water-cooled discharging end section 14, two solid intermediate sections 15, and an enlarged charging end section 16. The channel within the launder is disposed at a suitable angle to permit the molten material to flow readily into the furnace. The launders are substantially horizontally disposed, the outer ends being raised to a slightly higher elevation than the inner ends to cause the molten material to flow readily. The launders may form any suitable angle with the horizontal. The adjacent ends of the launder sections may be provided with flanges or other suitable joints for connecting them together. The outer end of the charging end section of the launder is provided with a wall 17 having a curved upper edge to receive a curved wall of a pouring receptacle or ladle.

The discharge end section 14 is provided with a cover 20 which may be removable or which may be formed integrally with the bottom portion. The section 14 is provided with a plurality of communicating conduits or passages 21 in its bottom and side walls. The conduits 21 communicate at one end with a header 22 and at the other end with a plurality of pipes 23 which project outwardly. The pipes 23 may be connected in any suitable manner with a source of supply of cold water (not shown). A discharge conduit 24 is connected to the header 22. The cover or top wall 20 is provided with a coil 25.

The launder sections are preferably formed by casting a metal such as copper or iron. The conduits 21 and 22 are preferably formed by incorporating metal pipes during the casting operation. The discharge conduit 24 and the inlet pipes 23 may also be incorporated in the structure during the casting operation.

The section 14 is provided with a slot or opening 26 in its top wall or cover 20, and a groove 27 is formed in the inner surface of the section adjacent and below the slot 26. A gate or closure member 30 is adapted to enter the slot 26 and groove 27, its side and bottom

edges being so formed as to engage the surface of the groove 27.

The gate 30 is pivotally attached to a piston rod 31 which is attached to a piston 32 within an air cylinder 33. The air cylinder 33 is mounted on a rigid supporting frame 34 above the launder in such a manner that the piston and piston rod may be reciprocated vertically.

When the device is in use, water is circulated through the discharge end section continuously, the water being introduced into the bottom and side walls through the pipes 23 and discharged through the conduit 24 and introduced into the top or cover through either end of the coil 25. During a charging operation, the charging opening formed by the side, bottom and top walls of the discharge section is open, the gate or closure member 30 being maintained in a raised position as shown in Fig. 5. When the charging has been completed, the gate or closure member 30 is permitted to enter the recess 27. The recess 27 is so located that a bar may be inserted to loosen and remove material which may solidify therein.

I claim:

1. The combination with a metallurgical furnace of a substantially horizontally disposed water-cooled charging conduit having a slot formed in its top wall and having a groove formed in its side and bottom walls adjacent the slot, and a substantially vertically movable gate mounted above the conduit and adapted to enter the slot and groove to close the passage in the conduit.

2. Apparatus for introducing molten materials into metallurgical furnaces comprising a launder having an enlarged open-top charging end portion and a covered discharge end portion, and a movable gate for closing the passage in the covered end portion.

3. Apparatus for introducing molten materials into metallurgical furnaces comprising a metal launder having an enlarged open-top charging end portion and a covered discharge end portion provided with one or more fluid passages, and a vertically movable gate for closing the passage in the covered end portion.

4. Apparatus for introducing molten materials into metallurgical furnaces comprising a metal launder having an enlarged open-top charging end portion provided with an end retaining wall and a covered discharge end portion provided with one or more fluid passages, and a vertically movable gate for closing the passage in the covered end portion.

5. Apparatus for introducing molten materials into metallurgical furnaces comprising a launder having an enlarged open-top charging end portion and a covered dis-

charge end portion provided with one or more fluid passages.

6. Apparatus for introducing molten materials into metallurgical furnaces comprising a launder having an enlarged open-top charging end portion provided with solid walls, and a covered discharge end portion provided with one or more fluid passages.

In testimony whereof I affix my signature.

CHARLES RAPHAEL KUZELL.
